UNITED STATES PATENT OFFICE

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS

DUPLICATING MACHINE

Application filed July 2, 1928. Serial No. 289,821.

This invention relates particularly to a machine adapted to the work of producing multiple copies of sales slips, order slips, accounting slips, etc.

More especially, the invention relates to a machine adapted to file, or store, the original and having means for deflecting and diverting the copies so that they are readily accessible at the side of the machine.

The primary object is to provide a machine of this character of improved general construction and operation and embodying numerous improved features.

A preferred embodiment of the invention is illustrated in the accompanying drawings, in which—

Fig. 1 is a broken perspective view of a duplicating machine, or register, embodying the invention, the cover-plates employed being shown in raised position; Fig. 2, a broken longitudinal vertical sectional view of the rear portion of the machine; Fig. 3, a transverse section taken as indicated at line 3 of Fig. 2; Fig. 4, a broken perspective view, partly in section, illustrating the strip-guide device employed for directing the strips from the supply rolls to the platen; Fig. 5, a broken horizontal section taken as indicated at line 5 of Fig. 4; Fig. 6, a broken transverse section taken as indicated at line 6 of Fig. 1; Fig. 7, a broken transverse section taken as indicated at line 7 of Fig. 1; Fig. 8, a broken view taken as indicated at line 8 of Fig. 7 and showing the hinge connections of a swinging member in which the upper feed-roll is mounted; Fig. 9, a broken section taken as indicated at line 9 of Fig. 7 and illustrating initial-feed segments employed; Fig. 10, a broken section taken as indicated at line 10 of Fig. 7; Fig. 11, a broken section taken as indicated at line 11—11 of Fig. 7; Fig. 12, a broken section taken as indicated at line 12 of Fig. 7; Fig. 13, a broken section taken as indicated at line 13 of Fig. 11, this view showing a gear and integral cams, one of which cams actuates the cutter and the other of which actuates impaling pins employed for filing purposes; Fig. 14, an enlarged broken longitudinal vertical sectional view taken as in-

dicated at line 14 of Fig. 1; Fig. 15, a broken sectional view similar to Fig. 14, but showing the position of the parts at the conclusion of the downward stroke of the knife; Fig. 16, a broken sectional view taken as indicated at line 16 of Fig. 1, this view illustrating a register-finger actuating-lever and a companion crank-latch; Fig. 17, a broken sectional view taken as indicated at line 17 of Fig. 16; Fig. 18, a broken sectional view, diagrammatic in its nature, illustrating the manner in which the original sales slip is overturned longitudinally in the filing compartment; Fig. 19, a transverse section taken as indicated at line 19 of Fig. 12; and Fig. 20, a broken perspective view illustrating the manner in which the strip-clamps and intervening knife are actuated.

In the preferred construction, A designates a casing having at its rear portion a strip-supply compartment A' and having at its advance end-portion a filing compartment A'; B, a platen supported on the casing above the chamber A', the platen having connected with its rear end a strip-guiding device B'; C, a cover-plate pivotally connected with the casing and provided with an opening C' giving access to the strips upon the platen, the member C being further provided at its front end with a housing C' adapted to house the feed-rolls and the cutting device employed for severing the upper or original strip into tickets; D, a lower feed-roll journaled in the upper portion of the casing in advance of the front end of the platen; E, an upper feed-roll journaled in a cross-member E' which is pivotally connected at 1 with the upper portion of one side of the casing; F, a crank-shaft equipped at one end with a crank F' and at the other end with a gear F'; G, a combination gear and cam, the toothed portion of which meshes with the gear F'; H, a pinion on one end of the lower feed-roll D which is actuated by the gear G, the opposite end of the feed-roll D being equipped with the gear 2 which meshes with the gear 3 on the upper feed-roll; I, a forked lever supported on a pivot 4 and actuated by the member G; J, a rock-member comprising a shaft J', a rearwardly extending actuating

arm J^2 , and forwardly extending arms J^3 the arm J^2 being connected by a link J^4 to the lever I ; K , a pair of vertical movable slides, or links, connected with the front ends 5 of the arms J^3 ; L and L' , a pair of spring depressed clamps which are adapted to be lifted by the links K ; L^2 , a knife disposed between the planes of the clamps and actuated by the links K ; M , a divider located in 10 advance of the feed-rolls and associated with the clamps and knife mentioned, said divider being adapted to deflect the copy-strips downwardly, while the original strip passes above the divider and beneath the clamps and knife; 15 N , a curved deflector adapted to direct the advance end of the original strip downwardly into position to be engaged by the impaling-fingers of the filing device; P , a flaring side-delivery chute; Q , a filing device located 20 in the filing compartment just back of the side-delivery chute P ; R , a slip-overturning device adapted to engage the severed original slip and deposit it face downward in the filing compartment; S , register-fingers fixedly mounted on a rock-shaft S' (Figs. 10 and 14); S^2 , a cam-lever mounted on a shaft, or stud, S^3 (Fig. 14) and engaging an arm 5 with which the rock-shaft S' is equipped, the cam-lever S^2 being normally held in the 25 position shown in Fig. 14 by means of a spring 6; S^4 , a link adapted to actuate the cam-lever S^2 , said link extending forwardly and being connected with an interiorly located arm S^5 (Figs. 16 and 17) secured to 30 a rock-shaft S^6 which has fixedly secured to its outer end a register-finger control lever S^7 ; T , a crank-latch associated with the lever S^7 and adapted to latch the crank F' in the position shown in Figs. 1 and 17; U (Fig. 40 17), a pinion mounted on the crank-shaft F adjacent the inner surface of the side-wall of the filing compartment, said pinion serving to actuate a gear-train composed of gears U' and U^2 , the gear U^2 being equipped with 45 a cam a adapted to actuate a slide U^3 which serves to actuate the device R ; and V (Fig. 11), a lever supported on a pivot 7, said lever being actuated by one of the cams of the member G and having its lower end equipped with 50 a stud 7^a adapted to actuate the filing device Q through the medium of an arm 8.

It may be stated here that the device Q is equipped with a strip-lifting arm 9 which has an upturned extremity 9^a adapted to 55 work through a perforation 10 in the bottom of the side-delivery chute P . The function of this device is to lift the copy-strips sufficiently away from the bottom of the chute P to enable them to be readily grasped by the 60 operator preparatory to tearing the copy-slips from the strips by means of engagement with a straight edge. Reference is made to Fig. 9.

The casing A preferably is made from sheet 65 aluminum, or other sheet-metal. It is shown

as comprising side walls 11 and removable end walls 12 and 13. At the front end of the compartment A' (Fig. 2) is a removably secured transverse wall 14 which is disposed just back of the lateral delivery-chute P . Within the compartment A' is a roll-supporting device comprising side-plates 15 and cross-rods 15^a. This forms a removable frame which can be withdrawn from the casing after the removal of the rear end 12. Between the lower portions of the plates 15 are secured inclined bottom plates 15^b. The original supply-roll 16 rests upon the rear-most bottom plate 15^b and against a pair of the cross-rods 15^a, and the original paper strip 16^a extends from the roll through the device B' and thence over the platen. 70 75 80

The copy-strip rolls 17 rest upon the other inclined bottom plates 15^b and the copy-strips 17^a extend therefrom through the device B' and across the platen. It will be noted that the front roll 17 bears against the cross-wall 14 and the intermediate roll bears against a pair of the cross-rods 15^a. 85

As most clearly shown in Fig. 6, the platen 90 B is in the form of a sheet-metal plate which has one lateral edge connected by means of a hinge 18 with the upper portion of one of the side walls of the casing. 95

The side wall of the casing is equipped below the hinge 18 with an open top receptacle 19 which contains the carbon strip roll 20. The carbon strips 20^a extend transversely across the platen and are interleaved with the paper strips. 100

The cover-plate C has one lateral edge-portion extending over the receptacle 19 and connected to the upper outer portion of said receptacle by a hinge 21. The metal of the cover-plate C is struck or bevelled downwardly adjacent the opening C' , thus providing a bevelled margin 22 for the opening. The cover-plate is shown equipped at its lower side with short posts 23 whose lower ends bear on the carbon strips and press them against the lateral margins of the platen, so that the carbons will be properly held against movement when the paper strips are fed therethrough. 105 110 115

The cover-plate C is equipped with a latch 24 which engages a slot with which the end wall 12 is provided. 120

The device B' (Figs. 2, 4 and 5) is pivotally connected with the rear end of the platen. The device B' comprises a U-shaped frame-member 25 whose forwardly extending arms are connected by means of a pintle 26 to lugs 27 which depend from the rear corners of the platen; and a series of guide-rolls 28 mounted in the U-shaped frame-member 25. In the illustration given, the rolls 28 are provided at their extremities with reduced extensions 28^a which are slidably mounted in slots 29 with which the arms of the frame-member 25 are provided. Said arms are also provided 125 130 135

with bores 30 which receive slidable plugs 31 which space the rolls 28. Between the front plugs 31 and the end-portions of the pintle 26 are confined coil-springs 32 which yieldingly hold the rolls in the position indicated in Fig. 5. The frame 25 has its arms provided with extensions 25^a which extend beneath the rear portion of the platen and afford stops. The connections are such that when the platen is 10 swung upwardly about the pivot 18, the device B' will be lifted with the platen. On the other hand, when the platen is in the horizontal position, the device B' may be swung upwardly about the pintle 26, if desired.

15 The side walls 11 of the casing are provided (Fig. 5) with inwardly extending studs 33 which afford supports for the rear portion of the device B'. A U-shaped straightener-bar 34 which has rearwardly 20 and upwardly extending arms is pivotally connected with the pins 33, and is adapted to be supported on studs 35 which extend inwardly from the side walls 11. The web of the member 34 is adapted to engage the original paper strip 16^a just below the rear guide-roll 28. The paper has a tendency to curve as it comes from the roll 16, and the purpose of the device 34 is to give it a reverse curve about the small diameter guide-roll, as shown. The 25 rolls 17 are located sufficiently forward to cause the copy-strips to be given reverse curves about the guide-rolls 28.

As appears in Fig. 4, the cover-plate C is equipped with short studs 36 adapted to bear 30 on the frame 25 and hold the device B' in the operative position.

In the filing compartment A², a spacing-member 37 is applied to the inner surface of one of the side walls (Fig. 1); and at the opposite side (Figs. 1 and 17), a gear housing-plate 38 is secured to the inner side of the casing-wall. The plate 38 is secured by means of screws 38^a to tapped studs 38^b which are riveted to the side wall of the casing.

45 The lower feed-roll D is journalled in bearings 39 (Fig. 7) which are secured to the side walls 11 above the delivery-chute P. The feed-roll E, as has been stated, is journalled in a supporting-member E' which is 50 adapted to be swung upwardly about the pivot 1. It will be noted that the pivot 1 is positioned to prevent the teeth of the gears 2 and 3 from disengaging when the supporting member E' is swung upwardly. Such an arrangement prevents the rolls from getting out of their timed relation. At the opposite end, the member E' is equipped with a spring pressed latch 40 which is pivotally connected to the member by means of a pin 40^a. The 55 latch is adapted to engage a lug 41 with which the side wall 11 is provided.

The rolls D and E are provided with normal feed-disks 42 and 43, respectively. These disks are adapted to rotate idly when 60 they encounter perforations 44 in the strips.

The rolls D and E are also provided with initial feed-segments 42^a and 43^a, respectively, these segments having radii corresponding with the radii of the disks 42 and 43, respectively. These segments are adapted to 70 come into gripping relation at the conclusion of a cycle of operations, so as to hold the strips gripped while the copy-slips are being torn from the strips. This position is shown in Fig. 9, and it will be understood that the segments are in position to initiate the feed of the strips when a new cycle of operations is begun. After the perforations 44 are carried beyond the normal feed-disks 42 and 43, the normal feeding of the strips is accomplished by said feed-disks.

75 The member E' is shown provided with slotted bearings 45 which receive the shaft of the upper feed-roll, the shaft being supported by means of pins 46. At the bearings, 80 the member E' is equipped with springs 47 which tend to depress the feed-roll E.

The crank-shaft F (Fig. 1) extends across the upper portion of the filing compartment A² just back of the deflector N which guides 85 the original strip downwardly into the filing compartment. The crank F' is shown equipped with a knob, or handle, 48.

At the opposite end of the crank-shaft is 90 the gear F² which actuates the idler gear G (Figs. 7, 11 and 13). As shown, the pinion H which actuates the lower feed-roll is driven by the gear G.

95 The gear G is journalled on a stub-shaft 49 which has one end extending through the adjacent side wall 11 and secured thereto by riveting, as indicated at 49^a in Fig. 13. The other end of the shaft 49 is supported in a perforation with which a cast-metal housing-plate 50 is provided. This plate is secured to the side wall 11 and forms therewith a housing for the gears located at this part of the machine.

The forked cam-actuated lever I is mounted 100 on the pivot 4. It has one arm 51 which engages a cam 52 of the member G, and has another arm 51^a which is adapted to be engaged by a stud, or roller, 53 with which the member G is equipped. The member G has 105 also formed integrally therewith a cam 54 which is adapted to actuate the lever V.

The arm 55 of the lever I is bent and works through a perforation 56 in the side wall 11; and, as appears from Fig. 12, the arm 55 is pivotally connected with the lower end 110 of the link J⁴ which serves to actuate the rock-member J. The shaft of the rock-member J is equipped with the previously mentioned forwardly extending arms J³ whose front ends are provided with pins 57 which engage slots 58 at the lower ends of the vertically sliding links K. The links K (Figs. 12 and 20) are provided at their upper portions with notches 59 which receive the projecting reduced end-portions 60 of the cut- 115

120

125

130

ter-blade L^2 . The clamping-members L and L' are provided, respectively, with reduced extensions 61 and 62 which are adapted to bear upon the upper end-surfaces of the links K ; and the lugs, or extensions, 61 and 62 are connected by means of coil-springs 63 (Fig. 1) with studs 64 with which the side walls of the casing are equipped. Thus, when the knife is lowered to sever the original strip, the clamping-members L and L' will be lowered upon the strips in advance of the severing operation. Thereupon, the knife will continue the downward movement. Upon the return stroke, after the knife has been withdrawn from the paper, the upper ends of the links K will encounter the projections 61 and 62 and the knife and clamping-members will complete the upstroke together.

20 The divider M is shown in Figs. 14 and 15. It comprises a cross-bar 65 which is secured at its ends to the side walls of the casing. It has a rearwardly presented tapering portion 66 which is adapted to separate the lower strips (copy-strips) 17^a from the upper or original strip 16^a. The divider is provided with a flat upper surface and has a steel inset shearing-bar 67. Adjacent the shearing-edge is a vertical slot 68 through which bits of paper can drop. The slot 68 is disposed immediately beneath the cutter-blade L^2 .

25 The member 65 is equipped with depending lugs 69 to which the upper portion of the front wall of the delivery-chute P is secured by means of screws 70. A strip-lifting device 71 is pivotally connected with the apex portion of the cross-bar 65. The member 71 consists of a strip of sheet-metal which is bent in triangular form, providing an upper wing 71^a and a lower wing 71^b. The apex portion is engaged by a pindle 72 while the wings embrace the upper and lower surfaces of the triangular portion of the bar 65. A small coil-spring 73 tends to lift the upper wing so that the advance edge of the original paper strip 16^a will cross the slot 68 without difficulty in the feeding operation. The lower wing is adapted to project across the lower end of the slot 68, so that the copy-strips will be guided across the slot without difficulty. The pindle 72 is held in position by clips 74 (Fig. 12).

30 As shown in Fig. 14, a bar 75 extends across the upper portion of the casing immediately back of the platen and forms a support for the strips of paper just below the meeting plane of the feed-rolls. The bar 75 is properly slotted to accommodate the lower feed-disks, the register-fingers, and the lower feed-segments. The bar is provided with a tearing edge 75^a disposed just back of the lower feed-roll on which the copy-slips may be severed from the lower strips of paper. It will be noted that the divider M and the bar 75 together form a throat, affording a pas-

sage 76 through which the copy-strips are deflected downwardly into the chute P , by which they are given a curl and diverted laterally to make the corner portions of the strip readily accessible at the large end of the chute P , which chute extends through an opening 77 (Fig. 1) in the side wall 11 of the casing.

As will be understood by reference to Figs. 1, 12 and 14, the side walls 11 of the casing are equipped at their inner sides with standards 78 which may, if desired, be cast integrally with the divider-bar 65, or which may be separately attached to the side walls, if desired. The clips 74 are secured to the upper ends of the standards, or posts, 78 by means of screws 79; and the clips have depending members 74^a which are spaced back of the posts 78 in a manner to form guides for the clamping-members L and L' and the interposed cutter-blade L^2 . As appears from Fig. 12, the members 74^a have offset lower end-portions which engage the ends of the pindle 72 upon which the combination guard and paper-lifter 71 is pivoted.

The divider-bar 65 has a bevelled front portion 80 above which is located the guide, or deflector, N , whose base-portion 81 is secured to the lower end-portions of the posts 78.

55 The delivery-chute P (Figs. 7, 11, 12 and 19) is preferably formed of sheet-metal. It has a small end 82 secured to one of the side walls 11 and a large end 83 which extends through the lateral opening 77 of the other side wall. The lower wall of the chute is inclined, as appears from Fig. 19, and the chute flares from its small end to the large end, so that as the copy-strips are deflected downwardly by the divider, they will be curled and diverted laterally, as suggested above.

60 The filing device Q (Figs. 11 and 18) comprises a rock-shaft 84 journaled in the lower portion of the filing compartment and equipped with a pair of filing-pins 84^a which are curved rearwardly at their upper portions. As previously explained, the shaft 84 is equipped with an arm 8 through the medium of which the impaling-pins 84^a are retracted in the manner illustrated in Fig. 11. The impaling-pins are permitted to move towards the divider M at the proper time to cause the pins to enter the punch-holes of the strip 16^a after the advance end of the strip has been curled downwardly by the deflector N . This will be understood from Fig. 15, from which it will be understood also that after the impaling-pins engage the punch-holes, the advance end of the strip 16^a is guided downwardly by the pins while the feeding of the strip continues.

65 The device R comprises a rock-shaft 85 journaled in the lower portion of the filing compartment just back of the impaling de-

vice; arms 86 extending upwardly from the rock-shaft adjacent the opposite sides of the casing and equipped with inturned extremities 86^a adapted to engage the strip in the manner shown in Fig. 18; and an arm 87 projecting forwardly from the rock-shaft and actuated through the medium of the cam-actuated slide U³.

As appears from Fig. 17, the rock-shaft 84 is equipped with a spring 84^b for actuating in one direction; and the rock-shaft 85 is equipped with a spring 85^a for actuating it in one direction.

As appears from Figs. 10 and 14, the register-fingers S which normally bear against the lower side of the lowermost strip of paper are yieldingly held in such position by a light spring 88 which is attached to the casing and to a short arm 89 with which the rock-shaft S' is equipped. At about the end of the feeding operation, the register-fingers enter the punch-holes 44. Normally this will occur just before the initial feed-segments grip the strips and while the normal feed-disks engage the punch-holes and thus work idly. This gives the strips opportunity for adjustment, or proper registration, it being understood that the guide-rolls 28 tend somewhat to retract the strips.

As appears from Fig. 14, the lever S² is adapted to retract the register-fingers. This action is accomplished through the medium of the rod S⁴, which, as shown in Fig. 17, connects with the arm S⁵ of the register-finger lever S⁷. Considering Figs. 1, 16 and 17, it will be noted that the crank latching-member T has a tubular pivot portion 90 pivoted on the shaft S⁶ of the register-finger actuating-lever, and has a bevelled notched latching portion 91 adapted to engage a portion 92 with which the crank-arm F' is equipped.

The arm S⁷ is equipped with a stud 93 which works in a short slot 94 with which the arm of the latch-member T is provided. The lever S⁷ and the latch-member T normally are held in the position shown in Fig. 17 by the rod S⁴ which is acted upon by the spring 6 shown in Fig. 14.

This is the position in which the crank-shaft is latched at the end of a cycle of operations. In this position, the arm S⁵ is engaged by the free end of an auxiliary latching-lever 96 which is supported by a pivot 97 connected with the side wall 11. The arm S⁵ is also provided with a shoulder 98 which is adapted to be engaged by the notch 95 of the latching-member 96 when the lever S⁷ and the crank-latch T are moved to release the crank. A spring 99 tends to draw the device 96 downwardly.

The crank-latch T is provided with a short arm 100 which is equipped with a pin 101 which works through a slot 102 in the side wall 11 of the casing. The inner end of the

stud 101 has connected therewith a spring 103 which tends to hold the crank-latch in the position shown in Fig. 17. When the crank is released, the auxiliary latch 96 drops so that the lug 104 thereof will rest upon a lever 105 which is connected by a pivot 106 to the side wall 11. In the operation of the crank, a cam 107 formed integrally with the gear U' serves to depress the end 105^a and thereby restore the member 96 to its first position. At the same time, the lever 105 lifts the pin 101 and thus holds the crank-latch out of the way until near the end of the cycle of operations, when the crank-latch is permitted to return to normal position so as to be ready to engage and latch the crank.

Before starting the cycle of operations, it is necessary to retract the lever S⁷ and thus draw the rod S⁴ to the right from the position shown in Fig. 14 so as to cause the lever S² to rock the shaft S' and withdraw the register-fingers. Shortly after the cycle of operations has started, it is necessary to release the register-pins and permit them to bear against the lower side of the strips of paper; and this is accomplished through the medium of the cam 107 which causes the lever 105 to lift the pawl, or latch, 96 so as to free it from engagement with the shoulder 98 of the lever S⁵. In the arrangement shown, however, the crank makes two revolutions in each cycle of operations; hence, it is necessary to hold the crank-latch T out of the way of the crank during passage of the crank; and this is accomplished by the lever 105 acting through the medium of the pin 101, which thus swings the crank-latch in timed relation to permit the crank to pass.

The filing compartment A² is adapted to be closed by a closure 108 which is pivotally connected with the front end of the casing by pivots 109. The closure 108 is equipped with a lock 110 whose bolt is adapted to engage a slot 111 in the side wall 11.

The operation of the machine may be described briefly:

The register-pins S are normally in the position shown in Figs. 7 and 10 when the crank is in the latched position shown in Fig. 1. The gears 2 and 3 have a gear ratio corresponding with the ratio of the normal feed-disks. Thus, the upper feed-rol E is adapted to turn more rapidly than the lower feed-rol D. In the illustration given, the upper feed-rol makes seven turns while the lower feed-rol makes five turns during the cycle of operations. To accomplish this, the crank makes two complete revolutions. The strips are initially passed over the platen and the punch-holes 44 at the advance ends of the strips are brought into engagement with the register-pins S. The cover-plate C is then lowered to and latched in the horizontal position.

In the illustration given, the crank makes

one complete turn in the operation of feeding the strips. This brings the next set of punch-holes 44 into registration with the normal feed-disks, whereupon these disks cease to effect feeding of the paper. During the next revolution of the crank-shaft, the feed-disks work idly, and during this time the clamping-members L and L' and the cutter-blade L² are actuated; also, the device R is actuated, after the original strip 16^a has been severed, to overturn the severed slip, and the filing-pins are then retracted so as to enable the next strip to be fed downwardly into position to be engaged by the filing-pins, when the filing-pins are again permitted to move to the impaling position. The copy-strips are deflected downwardly into and curled backwardly within the chute P and are diverted laterally by the chute, so that a corner portion projects through the lateral opening in the casing. The operator grasps the projecting corner of the copy-strips and by direct lateral pull severs the strips over the tearing-edge 75^a.
 25 From Fig. 14, it will be noted that the rear clamping-member L is disposed somewhat lower than the front clamping-member L'. Thus, the rear clamping-member engages the strip in advance of the front clamping-member; and after both clamping-members are seated, the knife operates to sever the paper. In the operation of lifting the clamps and knife, the blade is withdrawn, the front clamp starts to rise, and the rear clamp starts to rise an instant later.

To enable the crank to make a second revolution, the crank-latch T is held retracted through the medium of the pin 101 and the cam-actuated lever 105. Before the second revolution of the crank-shaft is completed, the crank-latch is permitted to return to normal position in readiness to engage and latch the crank.

The initial feed-segments 42^a and 43^a grip the strips at about the conclusion of the cycle of operations, so as to hold the strips firmly while the copy-strips are being severed and so as to be in readiness to initiate the feed of the strips in the next cycle of operations.

50 Ordinarily, the strips of paper are provided with printed forms and with punch-holes near the advance ends of the forms. These punch-holes are encountered by the normal feed-disks at the conclusion of a feeding operation and are also engaged by the register-fingers. In the next cycle of operations, the punch-holes of the original strip serve to receive the impaling-pins of the filing device, and the pins serve to guide the advance end of the strip downwardly and the strip is filed in the inverted position, or face downward.

55 While the machine illustrated is provided with a plurality of supply-rolls from which the strips of paper are taken, certain features

of the invention are not limited to a machine employing separate supply-rolls. The strips may be taken from any suitable supply source.

The machine described is simple and reliable, and is certain in operation. The feature of employing a register-finger releasing device and crank-latch closely associated therewith and adapted to be simultaneously actuated in the operation of releasing the crank constitutes a very important improvement from a practical standpoint; and the provision of means for holding the crank-latch in retracted position so that the crank can make a plurality of revolutions during the cycle of operations is a feature of practical importance. By gearing the crank-shaft to the feed-rolls in such manner that the feed-rolls are caused to rotate more rapidly than the crank-shaft, it is possible to employ comparatively small feed-disks, and the shearing-edge 75^a can be located a comparatively short distance from the point where the register-fingers engage the punch-holes, so that the copy-strips can be severed close enough to the punch-holes to avoid excessive margins beyond the punch-holes.

It may be added that in Fig. 17 a pawl 112 is shown in engagement with the gear U on the crank-shaft, this pawl serving to prevent retrograde movement of the crank, but permitting the crank-shaft to turn freely in the direction indicated by the arrow.

The foregoing detailed description has been given for clearness of understanding only and no unnecessary limitations should be understood therefrom, but the appended claims should be construed as broadly as permissible, in view of the prior art.

What I regard as new, and desire to secure by Letters Patent, is:

1. In a machine of the character set forth, a casing, a platen, mechanism for feeding punched strips across the platen, a register-finger yieldingly engaging the lower strip and adapted to engage the punch-holes, successively, a lever adapted to retract the register-finger, a hand-lever adjacent the outer surface of a side wall of the casing and having a shaft journalled in said side wall and equipped within the casing with an arm, and a link connecting said arm with said first-mentioned lever.

2. In a machine of the character set forth, a casing, a platen, mechanism for feeding punched strips across the platen, said mechanism including normal feed-disks adapted to engage the punch-holes and thereupon to work idly and including also a crank-shaft geared to and serving to actuate the feed-rolls, said crank-shaft being equipped with a crank, a register-pin yieldingly engaging the lowermost strip and adapted to engage the punch-holes in succession, a crank-latch and an associated register-pin releasing de-

vice, and means for temporarily holding the crank-latch and the register-pin releasing device in retracted position.

3. In a machine of the character set forth, a casing, a platen, mechanism for feeding punched strips across the platen, said mechanism including normal feed-disks adapted to engage the punch-holes and thereupon to work idly and including also a crank-shaft 10 geared to and serving to actuate the feed-rolls, said crank-shaft being equipped with a crank, a register-pin yieldingly engaging the lowermost strip and adapted to engage the punch-holes in succession, a crank-latch and 15 an associated register-pin releasing device, and means for temporarily holding the crank-latch and the register-pin releasing device in retracted position, said means being operative to release the register-pin releasing 20 device and permit the register-pin to engage the strip before the completion of the feeding operation.

4. In a machine of the character set forth, a casing; a platen; mechanism for feeding 25 punched strips across the platen, including feed-rolls provided with normal feed-disks adapted to work idly when they encounter punch-holes, initial feed-segments adapted to initiate the feed at the next cycle of operations, and a crank-shaft geared to and serving 30 to actuate the feed-rolls, said crank-shaft being equipped with a crank; a crank-latch adapted to engage and lock the crank at the end of a cycle of operations; and means actuated 35 through the medium of the crank-shaft for holding the crank-latch in retracted position while the crank is passing the latch to make a second revolution, said means being operative to permit the return of the crank-latch to normal position before the conclusion 40 of the cycle of operations.

5. In a machine of the character set forth, a casing; a platen; mechanism for feeding punched strips across the platen, including 45 feed-rolls provided with normal feed-disks adapted to work idly when they encounter punch-holes, initial feed-segments adapted to initiate the feed at the next cycle of operations, and a crank-shaft geared to and serving 50 to actuate the feed-rolls, said crank-shaft being equipped with a crank; a register-pin adapted to engage successive punch-holes; a register-pin releasing-lever having a shaft journalled in a side wall of the casing and 55 having means connected therewith for effecting release of the register-pin; a crank-latch journalled on the shaft of the register-pin releasing-lever, and lost motion means connecting said lever and said crank-latch 60 whereby the said lever may be moved independently of said crank-latch to return said register pin to normal position.

6. In a machine of the character set forth, a casing; a platen; mechanism for feeding 65 punched strips across the platen, said mech-

anism including feed-rolls and a crank geared to and serving to actuate the feed-rolls; a rock-shaft equipped with register-pins adapted to engage successive punch-holes, said rock-shaft being equipped with an actuating arm and also with a spring causing the register-pins to engage the lowermost strip of paper lightly; a second rock-shaft equipped with means adapted to engage 70 said actuating arm and cause retraction of said register-pins; a link connected with and adapted to turn said second-mentioned rock-shaft to effect release of said register-pins; and a lever adjacent the path of the crank, 75 said lever having connected therewith an arm with which said link is connected.

7. In a machine of the character set forth, a rock-shaft equipped with register-pins and an actuating arm; a second rock-shaft equipped with means for turning said first-mentioned rock-shaft through the medium 80 of said arm to retract the register-pins, a link connected with and extending forwardly from said second-mentioned rock-shaft; and a rock-member equipped with an actuating lever and equipped also with an arm connected with the forward end of said link.

8. In a machine of the character set forth, a casing; a register-finger; a crank-shaft journalled in said casing and equipped outside the casing with a crank; a register-finger retracting-lever having a shaft journalled in a side wall of the casing and equipped inside the casing with an arm; a link connecting said arm with said register-pin retracting means; a crank-latch pivoted on an axis concentric with said shaft and having lost-motion connection with said lever; an auxiliary latch controlling the position of said lever; a latch-actuating member; and means actuated by said crank-shaft and serving to actuate said auxiliary latch and 90 said latch-actuating member.

9. In means of the character set forth, a casing; strip-feeding rolls journalled in said casing; a crank-shaft journalled in said casing and journalled to said strip-feeding rolls, said crank-shaft being equipped adjacent one wall of the casing with a crank having at its extremity a catch; a register-finger 110 controlling-lever disposed adjacent the path of said catch and having a shaft journalled in the casing, said shaft being equipped at its inner end with an arm; a register-finger; means for retracting the register-finger; a link connecting said means with said arm; a crank-latch having a tubular shaft pivoted on the shaft of said lever and equipped with an actuating arm; an auxiliary latch mounted within the casing and controlling the position of said lever; a cam actuated through the medium of said crank-shaft; and a lever actuated through the medium of said cam and serving to release said auxiliary latch and to actuate said crank-latch to permit 115 120 125 130

passage of the crank at the beginning of a second revolution of the crank.

10. In a machine of the character set forth, a casing; strip-feeding mechanism; a lateral delivery-chute opening through a side wall of the casing; and a strip-lifting member associated with said chute.

11. In a machine of the character set forth, a casing; strip-feeding mechanism; a lateral delivery-chute beneath the strip-feeding mechanism; means for deflecting the strips downwardly into said chute; a strip-lifting member associated with said chute; and means actuated through the medium of the strip-feeding mechanism and serving to actuate said strip-lifting member.

12. In a machine of the character set forth, a casing; a platen; strip-feeding rolls; a crank-shaft geared to and serving to actuate said rolls; a filing compartment in advance of said platen; a rock-shaft equipped with a filing-pin and with a strip-lifting finger; a cam actuated through the medium of said crank-shaft and serving to actuate said rock-shaft; and a lateral delivery-chute opening through a side wall of the casing and with which said strip-lifting finger co-acts.

13. In a machine of the character set forth, a casing provided with a lateral delivery-chute and with a filing compartment; a rock-shaft pivoted in the lower portion of the casing and equipped with a strip-lifting finger working through an opening in the lower portion of said chute and equipped also with filing-pins; and means for actuating said rock-shaft.

14. In a machine of the character set forth, a casing; a platen; feed-rolls journaled in said casing at the advance end of said platen; a filing compartment in advance of said feed-rolls; a divider over which the original strip may pass to the filing compartment and beneath which copy-strips may be deflected, said divider being provided with a vertical slot; a knife reciprocably mounted above said divider and adapted to enter said slot; and a combination strip-lifter and guard pivotally mounted at the rear portion of said divider and having an upper wing adapted to lift the original strip and a lower wing adapted to guard the lower end of said slot.

15. In a machine of the character set forth, a casing; a pair of feed-rolls journaled therein; a divider extending transversely across the casing in advance of said feed-rolls and provided with a slot; a knife reciprocably mounted above said divider; and a paper-lifter associated with said divider and disposed between the feed-rolls and said slot.

16. In a machine of the character set forth, a casing; a pair of feed-rolls journaled therein; a divider extending transversely across the casing in advance of said feed-rolls and provided with a slot; a knife reciprocably mounted above said divider; and a

combination paper-lifter and slot-guarding member associated with said divider and having an apex portion presented towards the meeting plane of said feed-rolls.

17. In a machine of the character set forth, a platen; strip-feeding means; a divider immediately in advance of said strip-feeding means provided with a slot; a pair of clamping-members disposed above said divider; a cutter-blade interposed between said clamping-members; springs tending to depress said clamping-members; vertically movable slides connected with said cutter-blade and having means for lifting said clamping-members; a crank-shaft geared to said feed-rolls; a rock-shaft serving to actuate said slides; and a cam actuated through the medium of said crank-shaft and serving to actuate said rock-shaft.

18. In a machine of the character set forth, a casing; a platen; a pair of feed-rolls; a crank-shaft; gears connecting said crank-shaft and said feed-rolls, one of said gears being equipped with a cam; a lever actuated by said cam; a rock-shaft connected with and actuated by said lever; vertical slides actuated by said rock-shaft; a divider in advance of the platen and the feed rolls; and a knife above said divider connected with and actuated by said slides.

19. In a machine of the character set forth, a casing; a platen; a pair of feed-rolls; a crank-shaft; gears connecting said crank-shaft and said feed-rolls, one of said gears being equipped with a cam; a lever actuated by said cam; a rock-shaft connected with and actuated by said lever; vertical slides actuated by said rock-shaft; a divider in advance of the platen; and a pair of clamping-members and an interposed cutter-blade disposed above said divider and actuated by said slides.

20. In a machine of the character set forth, a casing, a platen, mechanism for feeding punched strips across the platen, a register-finger adapted to engage the punch-holes, a lever adapted to retract the register-finger, a hand-lever, an arm movable by said hand-lever, and a link connecting said arm with the first-mentioned lever.

21. In means of the character set forth, a feeding device comprising a lower feed-roll journaled in a frame, a supporting member pivoted to said frame and having an upper feed-roll journaled therein, said feed rolls being provided with intermeshing gears adjacent the pivot end, and said pivot positioned to prevent disengagement of the gears when the upper feed roll is swung away from said lower feed-roll.

22. In means of the character set forth, the combination of a main frame, a lower feed-shaft journaled therein, a frame-member having one end pivotally mounted on the main frame, an upper feed-shaft journaled in the pivoted frame-member, feed-disks fixed on

said shafts, initial feed-segments fixed on said shafts, and intermeshing gears on said shafts adjacent the pivot end of the pivoted frame-member, said gears remaining in mesh when
5 the pivoted frame-member is swung away from the lower feed-roll to permit insertion of paper.

LOUIS JENSEN.
